Specification for Design.

Patented Feb. 17, 1920.

Application filed November 15, 1919. Serial No. 338,387. Term of patent 14 years.

To all whom it may concern:

Be it known that I, JAMES CHRISTY, a citizen of the United States, residing at Cleveland, in the county of Cuyahoga and State of Ohio, have invented a new, original, and ornamental Design for Tires, of which the following is a specification, reference being had to the accompanying drawing, forming part thereof.

Figure 1 is a face view of a segmental

portion of the tire, Fig. 2 is a profile view on the longitudinal median line 2—2, Fig. 1, and Fig. 3 is a profile view transversely on line 3—3, Fig. 1, showing my new design for a tire.

I claim:

An ornamental design for a tire, as shown.

JAMES CHRISTY.
